(57) **CLAIM**

The ornamental design for a data transmission cable, as shown and described.

DESCRIPTION

FIG. 1 is a perspective view of the data transmission cable showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

In the drawings, the broken lines are for the purpose of illustrating portions of the data transmission cable that form no part of the claimed design. The data transmission cable is shown with a symbolic break in its length. The appearance of any portion of the article between the break lines forms no part of the claimed design.
